CLAIM

The ornamental design for a transmission for short cab and cab over type trucks, as shown and described.

DESCRIPTION

FIG. 1 is a front elevational view of a transmission adaptor for short cab and cab over type trucks showing my new design;

FIG. 2 is an enlarged right side elevational view, the left side being a mirror image thereof;

FIG. 3 is an enlarged top plan view, the bottom being a mirror image thereof;

FIG. 4 is a rear elevational view; and,

FIG. 5 is a rear perspective view thereof.

FIG. 1

FIG. 4

FIG. 3

FIG. 5

FIG. 2
